CLOTH-PLATE FOR A SEWING MACHINE

Nicholaus Knaus, Cranford, N. J., assignor to The Singer Manufacturing Company, Elizabeth, N. J., a corporation of New Jersey

Application March 26, 1951, Serial No. 14,624

Term of patent 14 years

(Cl. D70—2)

To all whom it may concern:

Be it known that I, Nicholaus Knaus, a citizen of the United States, residing at Cranford, in the county of Union and State of New Jersey, have invented a new, original, and ornamental Design for a Cloth-Plate for a Sewing Machine, of which the following is a specification, reference being had to the accompanying drawing, forming a part thereof.

In the drawings:

Fig. 1 is a front perspective view of a cloth-plate for a sewing machine.

Fig. 2 is a side elevational view of the cloth-plate shown in Fig. 1.

Those portions of Figs. 1 and 2 shown in dotted lines are for illustrative purposes only.

I claim:

The ornamental design for a cloth-plate for a sewing machine, as shown and described.

NICHOLAUS KNAUS.
